PIVOT HINGE FOR WINDOWS

Einar Särenholm, Eskilstuna, Sweden, assignor
to Svartviks Aktiebolag, Sundsvall, Sweden, a
corporation of Sweden

Application August 6, 1947, Serial No. 766,712
In Sweden May 12, 1943

Section 1, Public Law 690, August 8, 1946
Patent expires May 12, 1963

2 Claims. (Cl. 16—172)

1

The present invention relates to a pivot hinge for windows having a vertically swingable casement (or casements), wherein a hinge fitting is made to be arranged on the window frame and another to be arranged on the casement, and an intermediate member between the two hinge fittings is swingably suspended on one of said fittings while being connected to the other fitting in such a manner as to determine, when the hinge is arranged in its place, together with a stop limiting the swinging range thereof, a small opening position for the window (the ventilation position) while also permitting continued swinging of the window casement (casements) from this position into a position, wherein the outside of the window is turned inwardly, one of the places of connection on the intermediate member forming a pin and slot connection.

The substantial characteristic of the invention is, in the first place, that a slot comprised in the pin and slot connection is associated with an edge recess, with which a carrier member such as for example a pin is engaged, when the window is swung between the closed position to the small opening position or vice versa, said carrier member being moved out of said edge recess in swinging the window from the small opening position to a larger opening.

Furthermore, it will be possible, by suitably shaping the intermediate member and suitably locating the points of suspension, to provide tightening fillets between the window frame and the casement in such manner that untight points are eliminated about the hinge. Within the scope of the invention it is possible, furthermore, to attain such constructions of the hinge that perfect insulation is obtained against cold.

Further features characteristic of the invention and advantages inherent therein appear from the following description of an embodiment illustrated in the accompanying drawing. Fig. 1 is a side view showing a swingable window, the casement of which is adjusted in ventilation position. Fig. 2 is a side view of the same window with the window casement swung round in its entirety for cleaning or the like. Fig. 3 is a sectional view in an enlarged scale, of the hinge proper showing the position of certain parts of the hinge. Fig. 4 is a side view showing the configuration of the tightening fillets fitted into the sides of the window. Figs. 5 and 6 are side views showing the fitting of the hinge into the sides of the window frame and the window casement, respectively, and, Figs. 7 and 8 are diagrammatic views of the hinge showing different stages in the function of the hinge.

2

The hinge comprises two fittings 1 and 2 adapted to be fitted into the sides of the window frame and the window casement facing each other (Fig. 3), and an intermediate member 3 between the fittings 1 and 2, which is swingably suspended on the fitting 1 while being connected to the other fitting 2 in such manner as to determine, together with a fixed stop, here in the form of an abutment 4 secured on the fitting 1, a ventilation position for the window (Figs. 1 and 7) while also permitting continued swinging of the window casement from this position into a position, wherein the outside of the window is turned inwardly (Figs. 2 and 8).

In the embodiment shown, the connection between the fitting 2 and the intermediate member 3 is provided by means of a carrying pin 6, which is secured to the fitting 2 while resting in an edge recess or slot 15 in the intermediate member 3.

The latter is in turn suspended on the fitting 1 by means of a carrying pin 7, preferably in the form of a rivet. Furthermore, the fitting 2 has a carrier member arranged thereon, preferably in the form of a pin 5, and this member also engages the edge recess or curved slot 15 in the position of closure of the window (Fig. 5). As long as the carrier pin 5 bears on the edge of the recess 15, movement may be transmitted from the fitting 2 secured on the window casement to the intermediate member 3, so that the latter may be swung about the carrying pin 7. If the window casement is swung upwardly with its lower edge from its position of closure, the intermediate member 3 strikes against the fixed stop 4 (Fig. 7) and cannot then be turned further in the same direction. The window casement is thus suspended on both pins 6 and 7 at the same time and is thus retained in a definite position, the open position. If the swinging of the window casement is continued, the same now turns about the pin 6, the carrier pin 5 being thus caused to leave the recess 15 so as to take the position shown in Fig. 8, when the window is completely swung around. When the window is closed again, the carrier pin 5 is caused during the turning movement about the pin 6 to enter the edge recess 15 anew so as to bear on the edge thereof, so that the intermediate member 3 is entrained during the last portion of the movement and the turning movement is effected about the pin 1.

The intermediate member 3 is preferably formed as a circular sector and has its suspension point at the center of the circular arc. To this end, tightening fillets 13, 14, preferably in the form of wooden fillets arranged on the sides of the casement and the frame facing one another,

55

may be provided and formed as shown in Figs. 4, 5 and 6, the fillet 13 being mounted on the frame and the fillet 14 on the casement. It will be seen from Fig. 4 how the ends of the wooden fillets turned against each other are caused to bear on one another on a plane surface 8, after the window has been closed, and how the ends are formed to afford space for the movement of the intermediate member 3 formed as a circular sector. Covering of the gap between the ends of the fillets 13, 14 is obtained by an upwardly bent flange 16 at the peripheral portion of the intermediate member 3. Furthermore, the intermediate member is reinforced in the region about the edge recess 15 by a plate 9, which is secured by rivets 11, 12 to the intermediate member 3. The bearing surface of the pins 5, 6 is increased through this plate 9.

An easy and pleasing operation of the window is obtained through the intermediate member and the specific formation thereof and through the method of connecting the same with the fittings and, furthermore, the construction affords by the tightening fillets a perfect tightening fit against draught and insulation against cold. Because of the fact that the edge recess 15 is open, the window casement may also be readily hooked down from the hinges, if required.

The invention is not limited to the embodiment, shown in the drawing, said embodiment serving only as an elucidating example.

What I claim is:

1. In windows having a frame and a casement, a hinge for the suspension of the casement in the frame to enable swinging of the casement, said hinge comprising a hinge fitting mountable on the frame, a second hinge fitting mountable on the casement, an intermediate member swingably suspended and mounted on said frame fitting for supporting the casement on the inter-

mediate member, a pin on the casement fitting, said intermediate member having a slot with a lower wall and opening through the circumference of the intermediate member, said pin being mounted in said slot adjacent the lower wall, a stop for limiting the movement of the intermediate member and for determining a small opening position for the window, and an abutment member on the casement fitting adapted to carry along the intermediate member during the movement of the casement from a closed window position to said small opening position, said slot being adapted to receive the abutment member for actuation of the intermediate member and to release the abutment member for allowing the casement to be swung open further from said small opening position.

2. A hinge according to claim 1, in which the intermediate member has the shape of a sector of a circle and has its suspension point located in the proximity of the centre of the circle, the centre angle of the sector formed by the intermediate member plus the angle covered by said intermediate member in swinging the casement from its closed position to the open position being less than 180° together with the turning angle of the intermediate member at a swinging movement into the open position.

EINAR SÄRENHOLM.
